BACKBONE FOR A VELOCIPED

Filed June 24, 1935

UNITED STATES PATENT OFFICE

2,093,065

BACKBONE FOR A VELOCIPED

Bert J. Anderson, Hammond, Ind.

Application June 24, 1935, Serial No. 28,035

18 Claims. (Cl. 208—113)

This invention relates to an improvement in a backbone for a velocipede and has for one of its principal objects the provision of means for forming a backbone of two stampings.

5 Another and further important object of the backbone of this invention resides in the provision of means for crimping the head bushing over the edges of the stampings.

A still further important object of this invention resides in the fact that a grooved member is positioned on the head of the backbone to assist in securing the edges.

A still further object of importance and advantage resides in the provision of means for forming the edges of the stampings so they may be either welded or riveted together.

Still another object of importance resides in the provision of means for securing the rear end of the backbone to an axle supporting housing.

20 Additional objects of importance and advantage will be apparent from the following specification and the accompanying drawing, which show the preferred embodiment of this invention.

In the drawing:

25 Figure 1 is a side elevation of the backbone of this invention.

Figure 2 is a top plan view thereof.

Figure 3 is a bottom plan view of the backbone.

Figure 4 is a slightly enlarged sectional view 30 taken on the line 4—4 of Figure 1.

Figure 5 is a slightly enlarged vertical section taken on the line 5—5 of Figure 3.

Figure 6 is a slightly enlarged view of the head portion of the backbone with the grooved member 35 removed.

Figure 7 is a sectional view taken on the line 7—7 of Figure 1.

As shown in the drawing:

The reference numeral 10, indicates in a general way the backbone of this invention which, in the preferred embodiment, is constructed of a right hand stamping 12, and a left hand stamping 14, joined together.

The rear portion 16, of each stamping is 45 turned outwardly and the top portion thereof is perforated 18, as is best shown in Figures 2 and 3.

The central longitudinal portion of each stamping is substantially semi-oval in cross section with the upper and lower portions thereof flat and 50 adapted to be secured together as is best shown in Figure 7.

Positioned along each edge and parallel thereto is a plurality of holes which when the stampings are brought together register and are adapted 55 to receive rivets 20, for securing the stampings

in position, as is clearly shown in Figures 1, 4 and 6. It will be obvious however, that any other suitable means may be employed for this purpose.

A portion of the flat part of each stamping 12 and 14, intermediate the ends is curved outwardly to form a seat-post-receiving aperture 22.

Positioned in the forward portion of the backbone 10, is a steering-post-receiving bushing 24. The aperture for receiving the bushing being formed by curving the flat portion of the stampings 12 and 14, outwardly.

The bushing 24, is secured in position by crimping each end thereof over the adjacent edges of the stampings as is clearly shown in Figures 5 and 6.

A portion of each stamping forward of the bushing 24, is flat, as is indicated by the reference numeral 26, and preferably perforated as is best shown in Figure 6. In the preferred construction of the backbone of this invention 20 rivets 28, are used for securing these portions together, although it will be apparent that spot welding or any other suitable securing means may be employed.

Secured to the forward portion of the backbone 10, and extending therebeyond is a member 30, which has a groove 32, formed in its upper interior surface. The groove 32, in the member 30, is adapted to receive the forward edges 26, of the stampings and assist in securing them together and also to center the member 30, in position on the backbone. Portions of the lower edges of the member 30, are turned inwardly as is indicated by the reference numeral 34, and are adapted to contact the crimped edge of the bushing 24, and the forward portion of the backbone. The rear portions of the member 30, extend along the sides of the backbone to which they are secured, preferably by spot-welding.

It will be apparent that the member 30, when positioned on the backbone 10, greatly enhances its appearance and also increases its strength.

It will be further apparent that herein is provided a sectional backbone of great rigidity and exceedingly light in weight which because of its peculiar construction is exceptionally long lived.

Moreover it will be obvious from the construction shown in the preferred embodiment that the sections may be either spot-welded or riveted together.

I am aware that many changes may be made and numerous details of construction varied throughout a wide range without departing from the principles of this invention and I, therefore,

do not purpose limiting the patent granted hereon otherwise than as necessitated by the prior art.

I claim as my invention:

1. In a head for a sheet metal velocipede frame including a bushing, the ends of said bushing extending beyond the edges of the frame and being curled thereover, and a grooved member having rearwardly extending portions positioned over the forward part of the head.
2. In a head for a sheet metal velocipede frame including a bushing, the ends of said bushing extending beyond the edges of the frame and being curled thereover, and a grooved member having rearwardly extending portions positioned over the forward part of the head, said groove being adapted to receive the upper forward edges of said frame.
3. In a head for a sheet metal velocipede frame including a bushing, the ends of said bushing extending beyond the edges of the frame and being curled thereover, and a forward extending grooved member secured to the front of the frame, portions of the lower edges of said grooved member being turned inwardly and adapted to rest on the curled edge of the bushing.
4. A sheet metal backbone for a velocipede comprising side members substantially oval in cross section, the upper and lower edges of said members being flat and joined together, the rear end portion of each member being turned outwardly, each outwardly turned end portion having a substantially flat upper surface, the front end of said joined members being formed to receive a bushing, and a bushing positioned within said front end, the ends of said bushing being curled over the adjacent edges of said members.
5. A sheet metal backbone for a velocipede comprising side members substantially oval in cross section, the upper and lower edges of said members being flat and joined together, the rear portions of said members being curved outwardly, the upper edges of said outwardly curved rear portions being turned inwardly, the front portion of said joined members being formed to receive a bushing, and a bushing positioned within said formed front end.
6. A sheet metal backbone for a velocipede comprising side members substantially oval in cross section, portions of the front and the upper and lower edges of said members being flat and joined together, the rear portions of said members being curved outwardly and apertured, the upper edges of said outwardly curved rear portions being turned inwardly to form a relatively flat upper surface, the forward portion of said joined members being formed to receive a bushing, and a bushing positioned within said formed front end, the ends of said bushing being crimped over the adjacent edges of the joined members.
7. A sheet metal backbone for a velocipede comprising side members substantially oval in cross section, portions of the front and the upper and lower edges of said members being flat and joined together, the forward portion of said joined members being formed to receive a bushing, a bushing positioned within said formed front end, the ends of said bushing being crimped over the adjacent edges of the joined members, and a grooved member positioned over said flat front edges and projecting therebeyond.
8. In a head for a velocipede frame, a frame, a bushing positioned within said frame, the ends of said bushing being crimped over the adjacent portions of said frame, the front edge of each side of said frame projecting beyond said bush-
- ing, and means for securing the front edges of said frame together, said means including a member adapted to encircle the forward portion of said head.
9. In a head for a velocipede frame, a bushing, the ends of said bushing being crimped over the adjacent portions of said frame, and means for securing the front edges of said frame together, said means comprising a grooved member adapted to receive portions of the front edges of said frame.
10. A sheet metal backbone for a velocipede comprising side members substantially oval in cross section, portions of the front edge and the upper and lower edges of said members being flat and joined together, the forward portion of said joined members being formed to receive a bushing, a bushing positioned within said formed front end, the ends of said bushing being crimped over the adjacent edges of the joined members, and a grooved member positioned over said flat front edge and projecting therebeyond, portions of the lower edges of said grooved member being turned inwardly at right angles to the sides of said member.
11. A sheet metal backbone for a velocipede comprising side members having corresponding flat surfaces joined together, the forward portion of said joined members being formed to receive a bushing, a bushing positioned within said formed front end, the ends of said bushing being crimped over the adjacent edges of the joined members, a member projecting forwardly from the front portion of said joined members, and means for centering said projecting member in alignment with the longitudinal axis of said backbone.
12. A sheet metal backbone for a velocipede comprising side members having corresponding flat surfaces joined together, the forward portion of said joined members being formed to receive a bushing, a bushing positioned within said formed front end, the ends of said bushing being crimped over the adjacent edges of the joined members, a member projecting forwardly from the front portion of said joined members, and means for centering said projecting member in alignment with the longitudinal axis of said backbone, said means comprising forwardly projecting edges on the backbone and a coating groove in the projecting member.
13. A sheet metal backbone for a velocipede comprising side members substantially oval in cross section, the upper and lower edges of said members being flat and joined together, the rear end portion of each member being turned outwardly and apertured, the upper edge of each outwardly turned end portion being curved inwardly to produce a relatively flat inwardly extending upper surface, said apertures being located in said flat upper surfaces, the front end of said joined members being formed to receive a bushing, and a bushing positioned within said front end.
14. In a velocipede, a sheet metal head member having spaced apart parallel sides, and an inwardly projecting lug on the lower edge of each parallel side.
15. In a velocipede, a stamped head member substantially U-shaped in section, the sides of said member being spaced apart, and means for properly aligning said member with a velocipede frame.
16. In a velocipede, a stamped head member substantially U-shaped in horizontal section, the

front edge of said member being at an angle to the vertical, and means for maintaining the member in vertical alignment.

17. In a velocipede, a stamped head member substantially U-shaped in horizontal section, the front edge of said member being at an angle to the vertical, and means for maintaining the mem-

ber in vertical alignment, said means including a lug at the bottom edge of said member.

18. In a head member for a velocipede, a stamping having a sloping front and spaced apart parallel sides, and an inwardly projecting lug on the lower edge of each parallel side. 5

BERT J. ANDERSON.
